CLAIM

The ornamental design for a dispenser for tape or other roll goods, as shown and described.

DESCRIPTION

FIG. 1 is a right perspective view of a dispenser for tape or other roll goods;

FIG. 2 is a bottom view thereof;

FIG. 3 is a top view thereof;

FIG. 4 is a side view thereof, the left-side view being identical to the right-side view;

FIG. 5 is another top view thereof;

FIG. 6 is another bottom view thereof; and,

FIG. 7 is a right perspective view of the dispenser for tape or other roll goods in use.

The broken lines represent environmental subject matter showing claim in use and form no part of the claim.

1 Claim, 5 Drawing Sheets
